US00D768872S

(12) **United States Design Patent** (10) Patent No.: **US D768,872 S**
 (45) Date of Patent: ** *Oct. 11, 2016

(54) **CUVETTE FOR A WATER ANALYSIS INSTRUMENT**

(71) Applicant: **Hach Company**, Loveland, CO (US)

(72) Inventors: **Jeffrey Huhta**, Loveland, CO (US); **Steven J. Takacs**, Evans, CO (US); **Robert Stoughton**, Boulder, CO (US); **Rainer Frömel**, Troisdorf (DE); **Markus Lenhard**, Viersen (DE); **Isabel Hünig**, Düsseldorf (DE); **Ulrich Lundgreen**, Gütersloh (DE); **Aria Farjam**, Düsseldorf (DE)

(73) Assignee: **Hach Company**, Loveland, CO (US)

(*) Notice: This patent is subject to a terminal disclaimer.

(**) Term: **14 Years**

(21) Appl. No.: **29/497,679**

(22) Filed: **Jul. 28, 2014**

Related U.S. Application Data

(63) Continuation of application No. 29/439,569, filed on Dec. 12, 2012, now abandoned.

(51) **LOC (10) Cl.** **24-01**

(52) **U.S. Cl.**

USPC **D24/225**

(58) **Field of Classification Search**

(57) **CLAIM**

The ornamental design for a cuvette for a water analysis instrument, as shown and described.

DESCRIPTION

FIG. 1 is a perspective view of the ornamental design for a cuvette for a water analysis instrument.

FIG. 2 is a bottom view thereof.

FIG. 3 is a top view thereof.

FIG. 4 is a front view thereof.

FIG. 5 is a back view thereof.

FIG. 6 is a right view thereof; and,

FIG. 7 is a left view thereof.

The portion of the cuvette shown in broken lines form no part of the claimed design.

1 Claim, 5 Drawing Sheets
